UNITED STATES PATENT OFFICE.

CHARLES E. WEHN, OF ALAMEDA, AND HENRY W. LARSSON, OF OAKLAND, CALIFORNIA.

PENCIL.

Application filed April 21, 1920. Serial No. 375,646.

To all whom it may concern:

Be it known that we, CHARLES E. WEHN and HENRY W. LARSSON, citizens of the United States, residing at Alameda and Oakland, respectively, in the county of Alameda and State of California, have invented a new and useful Improvement in Pencils, of which the following is a specification.

10 This invention relates to a pencil and especially to improvements on the structure shown in Patent No. 1,302,999, issued May 12, 1919, entitled "Pencil," and in a pending application entitled "Pencil," filed

15 February 8, 1920, Serial No. 357,390.

One of the objects of the present invention is to provide a pencil of the feed or mechanical type which is simple and substantial in construction, cheap to manufacture, easy to manipulate, and so arranged that the lead may be readily advanced when worn or changed and replaced whenever desired.

Another object of the invention is to provide a novel form of screw feed mechanism for advancing the lead as the point becomes worn, and in conjunction therewith means for securing one of the screw feed members against rotation, said means also serving as a connector and reinforcing member for opposite sections of the pencil as will hereinafter be described.

Further objects will hereinafter appear.

The invention consists of the parts and the construction, combination and arrangement of parts as hereinafter more fully described and claimed, having reference to the accompanying drawings, in which—

Fig. 1 is a central vertical longitudinal section of the pencil, the member 7 being shown in full and a part thereof broken away.

Fig. 2 is a cross section on line 2—2, Fig. 1.

Fig. 3 is a detail view of the pencil cap.

Fig. 4 is a cross section on line 4—4, Fig. 3.

Fig. 5 is a perspective view of the keyway member.

Fig. 6 is a perspective view of the screw bar and the plunger whereby the lead is fed in a forward direction.

Fig. 7 is a perspective view showing the screw feed mechanism assembled.

Referring to the drawings in detail, A 55 indicates in general a mechanical type of pencil, which in this instance consists of two sections 2 and 3. Secured in the forward section 2 of the pencil is a lead receiving holder 4, and formed rearwardly thereof is 60 a passage 5, through which the lead feeding plunger or rod 6 extends. Connecting sections 2 and 3 is a holder 7. This holder is provided with a key-way 8 extending from end to end, in which is slidably mounted a 65 bar 9. This bar has threads 10 formed on its upper edge which are engaged by a nut 11 turnably mounted on the holder 7. This holder is circular in cross section, as shown in Figs. 2 and 5, and thereby forms a bearing 70 for the nut 11. As the bar 9 is adapted to slide in the keyway groove 8 of the combined holder and connecting bar 7, as will be later explained, each of the barrel sections 2 and 3 is provided with a keyway or 75 groove α , both of which keyways or grooves α align with the keyway or groove 8 in the connecting member 7.

For the purpose of forming a rigid connection between the pencil sections 2 and 3, 80 we provide a pair of ferrules or collars 12 and 13. These are secured on the central holder 7 by pinning, soldering or otherwise, and they are recessed as at 14 to receive the pencil sections 2 and 3 as shown, 85 said pencil sections 2 and 3 being shown in Fig. 1 secured by pins 21 but may be cemented, pinned or otherwise secured therein, and similarly secured to the holder 7. The upper section 3 of the pencil is recessed 90 as at 15 for the reception of the holder 7 and also to permit movement of the bar 9. This bar carries the pin or plunger 6 and may travel either in a forward or rearward direction by turning the nut 11 as desired. 95 Formed in the upper end of the section 3 is a lead receiving chamber 16, and forming a closure therefor is a cap 17. This cap is hollow as shown and it is provided with a sleeve extension 18, which is split as at 19 and slightly bulged as at 20, this bulge being adapted to register with a slight recess formed in the lead receiving chamber 16. The splits or grooves 19 formed in the sleeve permit yielding movement of the 100 bulged sections 20 and thereby forms a snap lock which secures the cover or cap 17 when applied in the chamber 16.

In actual operation if it is desired to insert a lead, it is only necessary to remove the cap 17 and one of the leads contained therein. The cap is then replaced and the 5 lead is inserted in the holder 4 by forcing it into a passage 4^a formed within the same, the bar 9 and the plunger 6 having been retracted by turning movement of the nut 11. Once the lead is inserted, it is possible to 10 feed it forwardly at any time by merely turning the nut. This nut is freely turnable upon the holder 7 and between the collars or ferrules 12 and 13, and as it engages the threaded portion of the bar 9, it can 15 readily be seen that this will travel in a forward direction and consequently force the lead in an outward direction through the holder 4, due to engagement of the plunger 6 therewith.

20 A simple substantial mechanism has in this manner been provided which is readily manipulated whether the lead is to be fed forward as worn, or whether it is desired to entirely remove the same to change the 25 lead.

The present invention contains several important features, first of all a pencil consisting of two sections 2 and 3, said sections being rigidly tied and braced with relation 30 to each other by the holder 7, and further by the ferrules or collar members 12 and 13 secured thereto. Second, the holder forms a part of the screw feed mechanism as it is secured against turning movement and serves 35 as a guide and receiver for the bar 9, having a threaded portion 10 formed thereon. Third, an exceedingly simple mechanism, cheap to manufacture and readily assembled has been provided. Fourth, a fool and tamper-proof 40 mechanism is also provided as access to the mechanism can not be obtained once the pencil is assembled and completed.

While any suitable form of cap may be employed as a closure for the lead receiving 45 chamber, we prefer the form here shown as it forms a snap lock which prevents accidental removal of the same. We similarly wish it understood that various changes in design and construction may be resorted to within 50 the scope of the appended claims; also that the materials and finish of the several parts employed may be such as the experience and judgment of the manufacturer may dictate or varying conditions may demand.

Having thus described our invention, what 55 we claim and desire to secure by Letters Patent is—

1. In a device of the character described, a pair of longitudinally spaced barrel sections, a member disposed within both of said barrel sections and having a longitudinal key-way formed therein, pins connecting the sections to said member, a nut of less length than either of the barrel sections and turnably mounted on said member and being un-

connected with the barrel sections and separating the inner ends of the latter, a hollow lead receiving holder connected to the outer end of one of the barrel sections and means carried in the key-way of said connecting member and actuated by said nut for advancing a lead through said holder.

2. In a device of the character described, a pair of longitudinally spaced barrel sections, a member disposed within both of said barrel sections and having a longitudinal key-way formed therein, a collar permanently fitted on the inner end of each section to reinforce the same, a nut of less length than the barrel sections and turnably mounted on said member between said collars and being unconnected with the barrel sections and collars, a hollow lead receiving holder having a reduced end fitted in the outer end of one of the barrel sections and means connected in the key-way of said connecting member and actuated by said nut for advancing a lead through said holder.

3. In a device of the character described, a pair of relatively long barrel sections, a member disposed within both of said barrel sections and having a longitudinal key-way formed through one wall thereof and opening through the ends of the member, the key-way including three closed sides, a collar fitted on the inner end of each section, devices connecting said collars and said sections and said member together, a nut of less length than either of the barrel sections turnably mounted on said member between said collars of the barrel sections to separate the inner ends of the latter and being unconnected with the collars, and barrel sections, a hollow lead receiving holder fitted in the outer end of one of the barrel sections, and a device slidable along the three closed walls of the key-way and actuated by said nut for advancing a lead through said holder.

4. A pencil comprising a pair of longitudinally interspaced barrel sections, a centrally disposed holder within the barrel sections and connecting the same, a keyway formed in said holder, a toothed bar slidable in said keyway, the teeth of which project beyond the surface of the holder, aligning keyways formed in the barrel sections to form a clearance for the teeth, a nut turnably mounted on the same between the barrel sections and separating the same longitudinally, said nut engaging the teeth of the bar only, a lead receiving holder in one of the barrel sections, and means on the bar adapted to engage a lead in said holder.

5. A pencil comprising a pair of longitudinally interspaced barrel sections, a centrally disposed holder within the barrel sections and connecting the same, a pair of interposed ferrules secured to the holder and to the respective barrel sections, a keyway formed in said holder, a toothed bar slidable

in said keyway, the teeth of which project beyond the surface of the holder, aligning keyways formed in the barrel sections and in the ferrules respectively to form a clearance for the teeth, a nut turnably mounted on the holder between the barrel sections and separating the same longitudinally, said nut engaging the teeth of the bar only, a lead receiving holder in one of the barrel sections, and means on the bar adapted to engage a lead in said holder.

6. A pencil comprising a pair of longitudinally interspaced barrel sections, a centrally disposed holder within the barrel sections and connecting the same, a pair of interposed ferrules, one on each end of the holder, said ferrules being secured to the holder and to the respective barrel sections, a keyway formed in said holder, a toothed bar slidable in said keyway, the teeth of which project beyond the surface of the holder, aligning keyways formed in the ferrule sections to form a clearance for the teeth, a nut turnably mounted on the holder between the barrel sections and separating the same longitudinally, said nut engaging the teeth of the bar only, a lead receiving holder in one of the barrel sections, and means on the bar adapted to engage a lead in said holder.

7. A pencil, comprising hollow barrel sec-

tions having alining key-ways, a member arranged interiorly of the sections, a lead receiving passage in the outer end of one of the barrel sections, the connecting member having a longitudinal groove extending through the same, a non-rotatable feed member having a flat portion slidable in the groove of the connecting member with said flat portion having threads on one edge and also having a reduced relatively long rod projecting from one end thereof adapted to slide in the lead receiving passage, said threads on the edge of the flat portion of the feed member extending into said alining key-ways of the sections, and a nut embracing the connecting member and filling the space between the inner ends of the barrel sections and adapted to engage the threads of the flat portion of the feed member so that upon rotation of the nut in one direction the feed member may slide so as to cause the rod portion of the feed member to advance the lead in the lead receiving passage.

In testimony whereof we have hereunto set our hands in the presence of two subscribing witnesses.
